Sam'l D. Vose of Albany N.Y.
Letters Patent No 465 Dated June 22nd 1862

Des. 465

The schedule referred to in these Letters Patent and making part of the same

To all whom it may concern;

Be it known that I Sam'l D. Vose of Albany
County of Albany, State of New York have invented or produced, a new ornamental
design for a Parlor Cook Stove, and I do hereby declare ^{that} the following is a full, & exact
description of the same reference being to the annexed drawings affixed to and making
part of this specification.

My invention consists in the combination of the several mouldings and ornaments
so arranged in the whole stove and is not easily described in words, reference is therefore

made to the drawings.

I do not claim any detailed part of the mouldings or configuration
What I claim as my invention and desire to secure by Letter Patent is the
combination of the several mouldings and ornaments as arranged together the whole forming an
ornamental design for a Parlor Book Stove as herein set forth and described.
